US0D1103918S

(12) **United States Design Patent** (10) Patent No.: **US D1,103,918 S**
(45) Date of Patent: ** Dec. 2, 2025

(54) **POWER BANK**

(71) Applicant: **Anker Innovations Technology Co., Ltd.**, Changsha (CN)

(72) Inventor: **Liyue Shang**, Shenzhen (CN)

(73) Assignee: **Anker Innovations Technology Co., Ltd.**, Changsha (CN)

(**) Term: **15 Years**

(21) Appl. No.: **29/949,115**

(22) Filed: **Jun. 25, 2024**

(30) **Foreign Application Priority Data**

Dec. 25, 2023 (CN) 202330851482.1

(51) LOC (15) Cl. **13-02**

(52) U.S. Cl.

USPC **D13/108**

(58) **Field of Classification Search**

USPC D13/102, 103, 107, 108, 110, 118, 119,

D13/184, 199; D14/251, 252

CPC H04B 1/3877; H04R 1/1025; H04M 1/06;

H02J 50/05

(57) **CLAIM**

The ornamental design for a power bank as shown and described.

DESCRIPTION

FIG. 1 is a front top perspective view of a power bank showing my new design;

FIG. 2 is a bottom rear perspective view thereof;

FIG. 3 is a right view thereof;

FIG. 4 is a left view thereof;

FIG. 5 is a front view thereof;

FIG. 6 is a rear view thereof;

FIG. 7 is a top view thereof;

FIG. 8 is a bottom view thereof; and,

FIG. 9 is a front top perspective view of the power bank of FIGS. 1-8 with outlet prongs shown in an alternate position. The broken lines depict portions of the power bank that form no part of the claimed design.

1 Claim, 9 Drawing Sheets
